CLAIM

The ornamental design for a bi-valve, as shown and described.

DESCRIPTION

FIG. 1 is a top perspective view of a bi-valve according to the present invention.

FIG. 2 is a bottom perspective view of the bi-valve of FIG. 1.

FIG. 3 is a front elevation view of the bi-valve of FIG. 1.

FIG. 4 is a rear elevation view of the bi-valve of FIG. 1.

FIG. 5 is a right side elevation view of the bi-valve of FIG. 1.

FIG. 6 is a left side elevation view of the bi-valve of FIG. 1.

FIG. 7 is a top view of the bi-valve of FIG. 1; and, FIG. 8 is a bottom view of the bi-valve of FIG. 1.

The features of the illustrated bi-valve shown in broken lines are for illustrative purposes only, and do not form part of the claimed design.

1 Claim, 5 Drawing Sheets
